UNITED STATES PATENT OFFICE

CHARLES B. BENNETT, OF PHILADELPHIA, PENNSYLVANIA, ASSIGNOR TO BENNETT MILLS, INCORPORATED, OF PHILADELPHIA, PENNSYLVANIA, A CORPORATION OF PENNSYLVANIA

DESIGN FOR A TEXTILE FABRIC

Application filed June 19, 1930. Serial No. 36,103. Term of patent 3½ years.

To all whom it may concern:

Be it known that I, CHARLES B. BENNETT, a citizen of the United States, residing in Philadelphia, Pennsylvania, have invented a certain new, original, and ornamental Design for Textile Fabrics, of which the following is a specification, reference being had to the accompanying drawing, forming part thereof, in which the figure is a face view of a textile fabric illustrating my new design, the extension in outline being identical in design with the full disclosure.

I claim:

The ornamental design for a textile fabric, substantially as shown.

CHARLES B. BENNETT.
